UNITED STATES PATENT OFFICE.

JOHN E. BELL, OF BROOKLYN, NEW YORK, ASSIGNOR TO POWER SPECIALTY COMPANY,
OF NEW YORK, N. Y., A CORPORATION OF NEW YORK.

SUPERHEATER.

Application filed June 17, 1919. Serial No. 304,775.

To all whom it may concern:

Be it known that I, JOHN E. BELL, a citizen of the United States, residing at Brooklyn, county of Kings, and State of New York, have invented certain new and useful Improvements in Superheaters, of which the following is a full, clear, and exact description.

As a general rule when a superheater is installed in a boiler it is intended to absorb as much of the furnace heat as possible, but there are practical limits to the amount of such heat as without special provision to prevent it the tubes would be burned out by too excessive a temperature. In this respect superheater tubes differ from the boiler tubes, the water in which protects them against high radiant and conducted heat, and to safeguard superheaters it is usual to place them in such position that a safe proportion of the furnace heat will be absorbed by a part or all of the boiler tubes before it is reached by the hot gases.

For this reason separately fired superheaters are not as a rule economical, although in many cases they may be extremely desirable, as the heat is apt to be too intense and liable to burn out the tubes. This is particularly true of the radiant heat.

I have discovered, and in a patent granted to me on March 11, 1919, No. 1,296,739, I have set forth a way to protect superheater tubes from excessive and radiant heat in a boiler by surrounding the tubes of the superheater with a heat conducting casing and exposing only so much of the latter to the action or effect of the radiant heat as will serve the purposes of a high degree of superheat without endangering the tubes, and in my present application I shall show a means of utilizing this principle in the construction of a practicable and efficient form of separately fired superheater, which enables me to construct and use such a device to great advantage, a result which has not so far as I am aware been heretofore accomplished.

According to my present invention I construct a furnace for a separately fired superheater, and form a horizontal partition wall therein, which is the part most exposed to radiant heat, largely of a protected superheater, of the kind above referred to, and above this wall I arrange an ordinary superheater arranged in the path of the hot gases

issuing from the first or fire compartment or chamber of the furnace, and flowing upward and transversely over the same to the flue. These superheaters may be connected up in various ways with the steam space of a boiler, that is to say, they may be in series or in multiple therewith, and such connections are not material to my invention provided they be such that both superheaters contribute to the ultimate result of superheating the steam.

I have illustrated my improvement as applied to an oiled fired superheater, but this, it will be understood, is not of the essence of the invention, as any other source of heat may be employed. I have also shown a special form of superheater, but this is only because that shown has been practically demonstrated to be most highly efficient and useful.

Certain features of the present invention are applicable to heaters in which a medium other than steam is heated.

In the drawing, Fig. 1 is a view in side elevation of the complete structure.

Fig. 2 is an end elevation of the same.

Fig. 3 is a vertical central longitudinal section.

Fig. 4 is a horizontal section, and

Fig. 5 is a vertical cross sectional view on two planes.

The structure is built up in the usual manner as a furnace with brick walls 1 suitably heat insulated in any approved manner, and having an opening in its front wall near the bottom of the fire chamber through which enters an oil burner 2.

The interior of the furnace is formed with two compartments, an upper or gas chamber and a lower or fire chamber, by means of a protected superheater comprising longitudinal horizontal tubes 3 enclosed in cast iron sections 4, the said sections at proper intervals being formed or provided with projections or eyes by means of which they are suspended from a transverse supporting beam 5, and above the protected tubes a wall of refractory material 6 which completes the partition which in this case is the ceiling of the lower compartment.

Above this superheater containing partition, and in the upper communicating compartment of the furnace is supported any desired form of ordinary superheater that shown comprising a series of inverted U-

tubes 7. These are supported by transverse beams of suitable character and are provided with proper braces, and in general the structure is equipped with the usual 5 means for supporting and strengthening its parts, and with the usual hand holes, doors and other devices for facilitating access to its interior.

The passage for the hot gases is longitudinally across the lower or fire compartment, upward around a vertical wall 8 at the end of the lower superheater, and transversely in the opposite direction through the upper or gas compartment and over the super- 15 heater tubes 7 to the outlet or flue 9.

As I have stated above, the special manner of connecting up either or both of the superheaters is largely immaterial. They may be in series or parallel or partly in either of 20 these relations, as may be preferable, and no new or unusual means are required for this purpose. The lower superheater is mainly affected by the radiant heat, while that in the upper compartment is wiped by the hot 25 gases on their path to the flue. As constructed and arranged, no part of the superheater as a whole is liable to injury from excessive heat, and this without regard to the velocity of the steam through the tubes.

30 The device has a high efficiency, is capable of producing a very high degree of superheat, and these results are attributable to the combination of the two forms or kinds of superheater, which neither could effect by 35 itself.

The tubes 3 form one heat absorbing surface of the heater and this surface is adapted to withstand but yet to absorb radiant heat from the fire chamber by reason of 40 the protective coverings 4. Tubes 7 constitute a second heat absorbing surface and the absorption of heat in this part of the heater is tempered by the absorption of heat by the first mentioned heating surface. The partition wall between the two surfaces serves 45 as a screen for the upper surface and pro-

tects the same against direct and high intensity radiant heat of the fire chamber.

What I claim as my invention is:

1. The combination with the furnace of a 50 separately fired superheater divided into two compartments, of a superheater constituting a part of the partition wall between the two compartments and the surface of which is adapted to withstand and absorb radiant 55 heat in the fire chamber, in an amount to substantially lower the temperature in said chamber, and an ordinary superheater located in the other compartment through which the hot gases pass from the first compartment or fire chamber, and connections 60 between the two superheaters through which the steam passes from one to the other superheater.

2. In fluid heating apparatus the combination 65 with a furnace divided into two compartments, one of which is a fire chamber and the other of which is traversed by the heating gases leaving the fire chamber, of a fluid container absorbing the major portion 70 of the available heat of the furnace and consisting of two sections, one of which is formed by pipes exposed to and designed to receive radiant heat direct from the fire chamber in amount sufficient to substantially 75 lower the temperature of the gases passing from the fire chamber to the other compartment, said pipes being surrounded by a metallic casing to strengthen the pipes and increase the amount of heat absorbed by the 80 fluid passing through the pipes, the other of said sections being formed by pipes disposed in said other compartment and receiving heat mainly by contact with the heating gases passing over them, and connection between the two sections through which the fluid heated passes from one section to the other. 85

In testimony whereof I hereunto affix my signature.

JOHN E. BELL.
